(57) **CLAIM**

The ornamental design for a connector, as shown and described.

DESCRIPTION

FIG. 1 is a front elevation view of a connector showing my new design;

FIG. 2 is a left perspective view towards the top thereof;

FIG. 3 is a right perspective view towards the top thereof;

FIG. 4 is a left side view thereof;

FIG. 5 is a top plan view thereof;

FIG. 6 is a right side view thereof;

FIG. 7 is a rear elevation view thereof; and,

FIG. 8 is bottom plan view thereof.

The broken line portion of the figure drawings is included to show unclaimed subject matter only and forms no part of the claimed design.
